UNITED STATES PATENT OFFICE.

THOMAS B. THOMPSON, OF CHICAGO, ILLINOIS, ASSIGNOR TO GULBRANSEN-DICKINSON COMPANY, OF CHICAGO, ILLINOIS, A CORPORATION OF ILLINOIS.

ADVERTISING DEVICE.

1,288,759.

Specification of Letters Patent. Patented Dec. 24, 1918.

Application filed May 20, 1918. Serial No. 235,686.

To all whom it may concern:

Be it known that I, THOMAS B. THOMPSON, a citizen of the United States, residing at Chicago, in the county of Cook and State 5 of Illinois, have invented a certain new, useful, and Improved Advertising Device, of which the following is a full, clear, concise, and exact description, reference being had to the accompanying drawings, forming a part 10 of this specification.

My invention relates to improvements in advertising devices, the object being to produce a device which shall arouse an inquisitive interest in the matter being advertised; 15 which shall carry or portray in suggestive form information of vital importance relating to the thing or article being advertised, and which shall be so attractive in appearance and suggestive as to result that 20 the beholder is influenced to investigate.

A further object of my invention is to provide a device for use in advertising player pianos, which device shall carry the suggestion that the piano can be easily played, 25 at least in so far as the mechanical operation of the bellows pedals is concerned.

My invention consists in a player piano having its bellows pedals in operative position and means for representing the application 30 to the pedals of a relatively small downward pressure and suggestive that the piano can be played by such a relatively small force.

My invention also consists in the representation 35 of a baby on hands and knees adjacent to the pedal of a player piano and having one hand above and preferably on one of the bellows pedals and representing the fact that the piano is so easily played 40 that even a baby can play it.

My invention also consists in a player piano having its bellows pedals extended in operative condition and a device representing the application of a slight force and provided 45 with a projecting part adapted to be positioned beneath a brace rod and with another part adapted to be positioned above one of the pedals and arranged to hold the pedal in partly depressed condition.

50 My invention also consists in the combinations and arrangements of parts and the features of construction by which I am enabled to attain the above mentioned and other objects, and all as hereinafter de-

scribed and particularly pointed out in the 55 appended claims.

My invention will be more readily understood by reference to the accompanying drawing and in which:

Figure 1 is a perspective view of a player 60 piano and a coöperating device illustrating one embodiment of my invention; and

Fig. 2 is a fragmentary vertical sectional view of the piano showing the device in operative relation to the bellows pedal. 65

In said drawings, 1 is an inner player piano, having bellows 2—2 within the lower part thereof, and a perforated music roll device 3 above. The bellows 2—2 are adapted to be operated by pedals 4 and 5. The 70 pedals are mounted on a frame having a front bar 6 and side brace rods 7 and 8. These rods are pivoted at their inner ends upon fixed brackets 9 and the frame with the pedals is adapted to be swung into the 75 lower part of the piano through the opening 10 or to be extended to operative position with the bar 6 resting upon the floor and the pedals in suitable inclined position to receive the feet of the person playing the 80 piano. The pedals are each hingedly mounted at their outer ends upon the front bar 6 and each is connected to one of the bellows by a link 11, so that as the pedal is depressed it will expand its bellows in an 85 obvious manner.

The brace rods 7 and 8 extend upwardly at their outer ends as at 12, thereby forming a space beneath the rod and above the floor.

To represent that the piano can be played 90 by a very slight pressure upon the pedals I prefer to provide a device 13 which in this instance represents a baby on its hands and knees; in other words, something which could not apply much force. The device 13 95 is provided with a projection 14, in this instance one of the hands of a baby, which is adapted to be placed upon the pedal 5 between its ends and suggesting that the baby can press the pedal. For the purpose of enhancing this simulation, I preferably provide the device 13 with a second projection 15, in this instance the other hand of the baby, adapted to project beneath the brace rod 8 between its ends and hold the device 100 13 from rising, or at least hold the end adjacent the pedal from rising, and I so relate the two projections 14 and 15 relatively 105

to the brace rod 8 and the surface of the 5 pedal 5 with which the projection 14 contacts, that the pedal 5 must be depressed in order to permit the placement of the device in position. The device once being placed in 10 position as shown, the upper hand will have the appearance of actually holding the pedal depressed. In order to more clearly show 15 that the pedal 5 is depressed, I have shown the pedal 4 in Fig. 2 in dotted lines in its normal position.

As clearly shown in Fig. 2 the device 13 is 10 relatively thin, in fact I prefer to make it of heavy paste-board, and provide a picture of 15 a baby as shown upon its outer face.

It should be understood that while I have 20 shown the device as held in position by the brace rod 8, this is not an essential feature of the invention, as the idea that the piano can be played by a slight pressure on the 25 pedals could be simulated by holding the device 13 in position in other ways and having the hand 14 resting upon the pedal. Consequently I do not limit or confine my 30 invention to the specific structures herein shown and described, except within the scope of the following claims.

Copies of this patent may be obtained for five cents each, by addressing the "Commissioner of Patents, Washington, D. C."

I claim:

1. The herein described improvements comprising the operating pedal of a manually operated device, in combination with 30 means arranged above the pedal and indicating that the pedal can be operated with a relatively small pressure.

2. The herein described improvements comprising the operating pedals of a player piano in operative position, in combination with means simulating the application of a slight pressure upon one pedal, as and for 40 the purpose specified.

3. The improvements herein described, comprising a player piano having its pedals extended in operative relation, a brace rod adapted to hold the pedals in such operating 45 relation, a device representing a relatively light weight or force and having a part engaged beneath the brace rod and another part in contact with one of its pedals and retaining it in partially depressed position.

In witness whereof I hereunto subscribe my name this 18th day of May, A. D. 1918.

THOMAS B. THOMPSON.
